ATTORNEYS

UNITED STATES PATENT OFFICE.

JOHN GOERGL, OF CHICAGO, ILLINOIS, ASSIGNOR OF ONE-HALF TO R. M. HVID, OF CHICAGO, ILLINOIS.

SAFETY SWITCH PLUG.

Application filed July 30, 1926, Serial No. 125,997. Renewed August 31, 1928.

My invention relates to improvements in safety switch plugs, and it consists in the combinations, constructions, and arrangements herein described and claimed.

5 An object of my invention is to provide a plug which may be used in connection with electric irons or other appliances of the type, and which contains switching mechanism by means of which the current may be cut off or 10 turned on at a predetermined temperature.

A further object of my invention is to provide a device of the type described in which the temperature at which the current is automatically cut off or turned on may be varied 15 so that in the case of an electric iron the heat may be regulated as desired and automatically maintained at a substantially given temperature.

20 A further object of my invention is to provide a plug, containing a thermostatic element which automatically moves to cut off or turn on the current with means for controlling the movement of the thermostatic element, so that it will operate at different 25 temperatures.

A further object is to provide a plug having the size of the ordinary plug, and which may be used with the ordinary electric iron or other electrical device that makes use of 30 plugs.

Other objects and advantages will appear in the following specification, and the novel features of the invention will be particularly pointed out in the appended claims.

35 My invention is illustrated in the accompanying drawings, forming part of this application, in which

Figure 1 is a side view of a plug, constructed according to my invention,

40 Figure 2 is a face view of one side of the plug,

Figure 3 is a sectional view along the line 3—3 of Figure 2,

45 Figure 4 is a face view of one half of the plug, looking along the line 4—4 of Figure 1 in the direction of the arrows,

Figure 5 is an enlarged sectional view 50 showing the thermostatic element and the spring for controlling the same.

Figure 6 is an enlarged sectional view through a portion of the spring contacts,

Figure 7 is a plan view of the spring contacts,

Figure 8 is a sectional view along the line 8—8 of Figure 3, and

Figures 9, 10 and 11 are detailed views of 55 conducting plates.

In carrying out my invention I make use of a plug having two portions A and B, which are made of hard rubber or other suitable insulating material, and which are held together by means of screw bolts 9. The section "B" has a through opening 7 therein, surrounded by a boss or enlargement 8, the opening being of such size as to receive the adjusting knob later to be described; this enables the part B which serves as a cover to be removed and replaced without interfering with the internal parts. As will be observed 60 from Figure 3, the section A is recessed to provide for a condenser 10, whose opposite ends have connected therewith conducting pins 11 and 12, respectively. The portion B is also recessed, and between the portions A and B are the three conducting plates 13, 14 and 15, shown in Figures 9, 10 and 11. The plate 13 lies next to the wall of the portion B, (see Figures 3 and 5). This plate has one corner bent up to form a hook 13^a, by means of which one of the sets of spring contacts is secured. The form of these spring 65 contacts is shown in Figures 6 and 7. It will be observed that there is a strip 16 which has a semi-circular portion 16^a stamped thereon and that to this strip is another strip 17, having a spring portion 17^a bent in the manner 70 shown in Figure 6, so that when a conducting terminal pin enters from the bottom, the spring 17^a will be moved aside and will form a close contact with the pin, which is pressed upon the conducting side 16^a. As will be 75 seen from Figure 3, this spring contact is secured to the up-turned portion 13^a by means of a screw. The lower end of the contact 16^a fits into a recess in the assembled plug sections and is, therefore, held securely.

Referring now again to Figures 3, 5 and 8, it will be seen that the plates 13, 14 and 15 are separated by suitable insulation. The central plate 14 has a conducting terminal 80 18, which extends through an opening 19 in the plate 13; the latter is provided with a 100

thermostatic rod or arm 20, which is made of metal and which, when heated, tends to spring away from the terminal 18 and when cooled tends to contact with it. This strip 5 may be of any suitable material, such as a compound metal strip, and it is pressed upon normally by a spring 21, which is secured at 10 22 to the plate 13. The upper end of the spring is arranged to be engaged by the end 15 of a screw 23, which is carried by a milled insulating knob 24. The latter is pressed on by a spring 25, which tends to push the head outwardly thus exerting friction on the threads of the screw so as to hold the latter 20 in adjusted position. In Figure 5 the thermostatic element 20 is shown away from the terminal. When the spring 21 is forced by the screw 23 toward the thermostatic element, it will require a greater amount of heat for 25 the latter to leave the terminal. The screw 23 engages with a threaded aperture in a bridge 13^b, the ends of which are secured by screws 13^c, to the plate 13; a boss 13^d on the bridge surrounds the threaded aperture and 30 serves to center and hold the spring 25. The outer end of the spring is held beneath the skirt 24^a at the margin of the knob 24.

The three plates 13, 14 and 15, as stated, 35 are insulated from each other and are held in spaced relation by means of screws 26, which pass through the conducting plates, but do not electrically connect them, as shown in Figure 8.

A spring socket contact 16^b, similar to the 40 spring contact 16^a, is secured to plate 15 in substantial alignment with the contact 16^a.

The condenser is connected with the plate 14 on one side and the plate 13 on the other.

From the foregoing description of the various parts of the device, the operation thereof 45 may be readily understood. When the parts are assembled, the plates 15 and 14 are connected to the wires leading from the source of current. As has been stated, the sockets, 50 which receive the terminal pins of the electrical device such as electric iron, are carried by the plates 15 and 13 respectively. Normally, the thermostatic element 20 is in engagement with the terminal 18, thereby closing the circuit through the plates 13 and 14 and hence closing the circuit through the electrical device. When, now, the thermostatic 55 element reaches a certain temperature, it will move away from the terminal 18, and this will cause the breaking of the circuit. In order to prevent arcing, I provide the condenser 19, which will permit the break to be made without arcing and destroying the contacts. When it is desired to make the 60 automatic circuit opener operate at a higher temperature, then the milled thumb knob 24 is turned to the right, forcing the spring 21 against the thermostatic arm, so that in the subsequent operation of the device greater

force must be exerted by the thermostatic arm to move away from the contact 18. In 65 other words, the arm which is reinforced by the spring may be made to operate at various desired temperatures.

It will thus be seen that my improved plug 70 not only embodies an automatic switch for operating at a predetermined temperature, but it also provides for the regulation of the temperature, or the adjustment to various temperatures so as to give more or less heat 75 where an iron is being used.

I claim:

1. A switch plug, comprising a pair of insulating sections, one of said sections having a boss provided with an opening, a stationary contact carried within said plug, a thermostatically actuated arm having one end normally in engagement with said contact and adapted to move away from said contact at a predetermined temperature, a spring for opposing said movement, a screw in engagement with said spring, an insulating knob surrounding the head of the screw and secured thereto for operating the screw, said screw being receivable in the opening in said boss, and a spring for exerting pressure on the knob to maintain the screw in its adjusted positions.

2. A switch plug, comprising a pair of insulating sections one of said sections having a boss provided with an opening, a stationary contact carried within said plug, a thermostatically actuated arm having one end normally in engagement with said contact and adapted to move away from said contact at a predetermined temperature, a spring for opposing said movement, a screw in engagement with said spring, an insulating knob surrounding the head of the screw being receivable in the opening in said boss, and means for frictionally maintaining the screw in its adjusted position.

3. A switch plug, comprising in combination, a pair of insulating sections, one of said sections having a lateral opening, a stationary contact carried within the said plug, a thermostatically actuated arm having one end normally in engagement with said contact and adapted to move away from said contact at a pre-determined temperature, a spring for opposing said movement, a bridge overlying said contact, a screw engaging said bridge, and adapted to contact said spring, a knob for actuating said screw, and means for maintaining said knob and screw in adjusted positions, the opening through said section being of a size to permit said knob to pass therethrough.

4. A plug comprising, in combination, a main section and a cover section, said cover section having an opening, a stationary contact, a movable contact, said movable contact being in the form of a bimetal arm, said

contacts being normally in engagement and said movable contact being adapted to move away from said stationary contact at a pre-determined temperature, a spring for opposing said movement, a bridge overlying said contacts, a screw engaging said bridge and contacting said spring, a knob for actuating said screw, all of said parts being fixed to said main section, said cover section overlying said parts, and the opening therein serving to accommodate said adjusting screw whereby said cover section may be removed without interfering with the operating parts. JOHN GOERGL.
